UNITED STATES PATENT OFFICE.

PETER F. FLEMING, OF HUNTSVILLE, MISSOURI, ASSIGNOR OF ONE-HALF TO
W. E. WADE AND W. T. DAMERSON, BOTH OF SAME PLACE.

MACHINE FOR CUTTING AND CARRYING CORN.

SPECIFICATION forming part of Letters Patent No. 433,121, dated July 29, 1890.

Application filed November 29, 1889. Serial No. 331,893. (No model.)

To all whom it may concern:

Be it known that I, PETER F. FLEMING, a citizen of the United States, residing at Huntsville, in the county of Randolph and State of Missouri, have invented certain new and useful Improvements in Machines for Cutting and Carrying Corn; and I do hereby declare that the following is a full, clear, and exact description of the same, reference being had to the annexed drawings, making a part of this specification, and to the letters of reference marked thereon.

This invention relates to certain new and useful improvements in machines for cutting and shocking corn.

The novelty resides in the peculiar combinations and the construction, arrangement, and adaption of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a top plan of the device embodying my improvements. Fig. 2 is a side view thereof. Fig. 3 is a detail in under plan, showing the manner of adjusting the saws or cutters. Fig 4 is a detail in end elevation of one of the tilting racks.

Like letters of reference indicate like parts throughout the several views.

Referring now to the details of the drawings by letter, A designates a suitable frame or platform supported upon the two rear wheels B and the front wheel C, the wheel C being carried by a transverse shaft *a*, journaled in the lower ends of the bifurcations of a hanger *b*, to the front end of which is attached, on a transverse shaft or pin *c*, the draft attachment D. Rigidly attached to this hanger is the vertical pin E, which is free to turn in bearings in the arms F, secured to the front end of the platform, as shown in Figs. 1 and 2. The upper end of this pin E is provided with a nut *d* to hold it against displacement. By this construction it will be seen that the draft is applied directly to the front wheel C, which can turn only as the horse turns, and which thus makes the machine

more rigid in the way of swaying sidewise in case only one of the knives hereinafter described is used, making the machine run steadier and give a better cut.

At the forward end of the platform are the standards G, suitably braced by the braces *e*, and further braced by means of the cross-bar H, which connects the upper ends of the standards, and the ends of which extend rearward, as shown at *f*, to form handles for the operators to hold onto as the machine is in operation. These standards and braces also serve as guards to keep the hands of the operators off of the knives in gathering in the cut corn.

Across the upper face of the platform, toward the rear thereof, are the cross bars or timbers I, near each end of which is pivoted one end of the short bars J on a longitudinal pivot *g*, and to the other ends of these short bars is rigidly secured the longitudinal timber or bar K, one on each side of the machine. These longitudinal timbers are provided with a plurality of diverging arms L, preferably rounded, as shown, the timbers and arms forming racks to receive the corn, as will hereinafter appear. The ends of the short bars J near their pivots are rounded, as shown at *h*, to aid them in turning over, as clearly shown in Figs. 2 and 4.

Across the upper face of the platform, near its front end, I secure a bar *i*, which serves as a brace for the feet of the operators.

Are the cutters, which may be either knives or saws, as may be preferred. There is one on each side of the machine, and as they are both alike and operate in the same manner a description of one will suffice for both. The knife or saw M is rigidly attached to an arm N, and extends at an angle to the line of draft, as shown in the drawings. It is braced near its outer end to the arm N by means of a brace-bar *j*, the said arm N being pivotally connected to the under side of the platform by means of a vertical pivot-pin *k*, and at its rear end formed with a lateral portion *l*, provided with a plurality of holes *m*, and working above a keeper or plate *n*, perforated for the reception of a removable pin *o*, which is designed to pass through an opening in the lateral portion of the arm N to hold it in its

adjusted position. This pin passes through the platform, and by removing the said pin the angle of the saw or knife can be changed to suit the character of rows of corn which it is desired to cut, and by inserting the pin in the proper hole keep the knife in such position.

The knife M is extended downward as well as rearward, as shown in Fig. 2, to give an upward and rearward impetus to the corn as it is cut, and also to allow of its swinging under the platform when it is desired to have it do so, for the purpose of transportation or storage, by simply removing the pin and swinging the arm N on its pivot.

The operation is simple and apparent. The draft is applied and the machine drawn forward between two rows of standing corn, two men being on the platform, one near each side at the forward end, and standing inside the guards or standards G G. The forward movement of the machine causes the knives or saws to come in contact with the corn and cut it off. As the corn is cut, the hands of the operators catch it and lay it back on the racks, and when they are full the horse is stopped and the racks tilted, as shown in Fig. 1, by taking hold of one of the inside arms L and lifting on the same, which will cause the 30 rack to tilt, and the corn thereon will slide

off onto the ground into a straight pile, so that it can be easily picked up and put in shock. Of course the racks might be tilted without stopping the machine; but it is preferred to stop the horse while tilting the racks.

35

What I claim as new is—

1. The combination, with the frame and the cross-bars, of the short bars pivoted at their outer ends on horizontal pivots passed through the said short bars to the ends of the cross-bars, the longitudinal timbers connecting the other ends of the short bars, and the divergent arms on the longitudinal timbers, substantially as described.

2. The combination, with the platform and the cross-bars upon the upper face thereof, of the short bars pivoted at their outer ends to the ends of the cross-bars upon longitudinal pivots and having one end rounded and at a distance above the platform, the longitudinal timbers connecting the outer or free ends of the short bars, and the arms on the longitudinal timbers, substantially as described.

In testimony that I claim the above I have hereunto subscribed my name in the presence of two witnesses.

PETER F. FLEMING.
